UNITED STATES PATENT OFFICE

2,464,618

FACSIMILE SYNCHRONIZING CONTROL

John R. Shonnard and George W. Kaye, New York, N. Y., assignors to Times Facsimile Corporation, a corporation of New York

Application September 7, 1945, Serial No. 615,006

9 Claims. (Cl. 178—69.5)

1

This invention relates to telegraph machines and more especially to driving and phasing arrangements for facsimile scanning drums and the like.

In the operation of facsimile systems employing rotating scanning drums, it is usually requisite before the start of a transmission period to phase the drums at the transmitter and receiver, even though the drums otherwise would run in perfect speed synchronism. This phasing operation is particularly important where one of the drums is comparatively heavy, or where the drum rotates at such a high speed as to have considerable inertia. This problem of phasing has been found to be particularly difficult with large or heavy drums because of the comparatively great and sudden load which is placed upon the driving mechanism at the instant of phasing. Heretofore, the phasing operation has required almost an instantaneous change from no load to full load on the driving motor and on the clutch between the motor and the drum. Since such clutches are usually of the slip-friction type, it is clear that this sudden change from no load to full load is represented by a considerable slip in the clutch with a consequent undesirable change in phase between the received phasing impulse and the actual angular phase of the drum.

There is disclosed in U. S. Patent #2,421,438, a novel form of drive-coupling between a slip-friction clutch and a scanning drum whereby the load on the clutch of the driving motor is materially reduced during phasing operations and the like.

Accordingly, it is a principal object of the present invention to provide an improvement on the clutching and phasing arrangement disclosed in said U. S. Patent #2,421,438.

Another object is to provide a drive-coupling between a motor and a scanning drum or the like, which under certain conditions, is allowed to coast freely, in conjunction with novel means for imparting positive driving force to the coasting drum at timed intervals.

Another object is to provide an improved phasing control mechanism whereby a scanning drum can coast while its associated driving clutch is declutched, and wherein special means are provided to insure that the coasting speed does not drop below a certain amount when the clutch is subsequently operated to clutching position.

A feature of the invention relates to a drive-coupling between a motor and a scanning drum, including a slip-friction clutch having an ele-

2

ment which can be selectively stopped, said element being coupled to the drum by a special one-way latch, whereby under certain conditions, the drum can freely coast; in conjunction with another member frictionally driven from said clutch and having automatically operable means for imparting positive driving torque to the drum to maintain its coasting speed above a predetermined amount.

10 A further feature relates to a novel combination of slip-friction clutches and latching control means whereby a scanning drum or the like can be selectively clutched to a driving shaft with a minimum of slippage or lost motion between the drum and the driving shaft, and with a minimum of load on the driving motor at the instant of clutching.

15 A still further feature relates to the novel organization and relative location and interconnection of parts which cooperate to provide an improved and highly accurate phasing control arrangement for telegraph machines, facsimile scanners and the like.

20 Other features and advantages not particularly enumerated will be apparent after a consideration of the following detailed descriptions and the appended claims.

In the drawing, which represents one preferred embodiment,

25 Fig. 1 shows the general arrangement of the more important parts of the clutches, and the drum driving and coasting control arrangement according to the invention.

30 Fig. 2 is a right-hand end view of the drum of Fig. 1.

35 Fig. 3 is an exploded perspective view to show more clearly the construction of the secondary or coasting control clutch.

40 Fig. 4 is a perspective view of part of Fig. 1 to show how the secondary clutch is momentarily released during each revolution of the drum shaft.

45 Fig. 5 is another view of Fig. 4.

Fig. 6 is a detailed view, partly sectional, along the line 6—6 of Fig. 5, showing the friction members of the secondary clutch.

50 Referring to the drawing, the driving motor 1 is connected to the main drum driving shaft 2, through the intermediary of a worm 3, and a cooperating worm-wheel 4, shaft 2 being supported in suitable anti-friction bearings in the standards 5, 6. Shaft 2 carries at its right-hand end a slip-friction clutch designated generally by the numeral 7 and described in detail in U. S. Patent #2,421,925. In general, this clutch com-

prises a set of three friction discs 8, 9 and 10. Discs 8 and 9 are appropriately fastened to shaft 2, while disc 10 is not connected to the shaft but is driven by frictional engagement with discs 8 and 9. Firmly attached to member 10 is a rigid stop arm 11, which has an inclined trailing face 12. The stopping of disc 10 is controlled by the armature 12a of an electromagnet 12b which magnet can be normally continuously energized so as to maintain its armature 12a out of the path of stop arm 11. When disc 10 and arm 11 are released for rotation, said arm is adapted to engage the left-hand end of a latch 13 which is pivotally mounted on a pin 14 in a slotted guide or stud 15, rigidly fastened to the drum driving plate 16. By means of a suitable spring (not shown), the latch 13 is normally held in the position shown in Fig. 1.

Plate 16 is fastened to drum shaft 17 which is journaled at opposite ends in suitable ball bearings in standards 18, 19. Preferably, the right-hand end of shaft 17 is provided with an end thrust ball bearing and the proper pressure being obtained by a suitable spring (Fig. 5) between the member 18 and a shoulder on shaft 17. Shaft 17 carries the usual lead screw 20, and at its right-hand end is slotted at 21, the scanning drum 22 being slidably keyed thereto so that as shaft 17 turns, the scanning drum also turns and advances along the shaft as determined by the pitch of the lead screw thread 20. For a detailed description of a preferred drum and lead screw arrangement, reference may be had to U. S. Patent No. 2,138,784, the disclosure of which is expressly incorporated herein by reference.

Plate 16 has another latch member 23 pivotally mounted on a pin 24 and within a radial slot on the periphery of plate 16 (Fig. 4). By means of a suitable biasing spring (not shown), the latch 23 is normally held in the position shown in Figs. 1 and 4, where it rests in a notch between adjacent teeth 25 on a collar 26 which forms part of the secondary or coasting control clutch. As shown in Fig. 6, collar 26 is arranged to be frictionally driven by means of a friction plate 27, which is secured by screws 28 to the plate 29 forming part of the main clutch member 9.

As shown more clearly in Figs. 1, 4 and 5, the left-hand face of member 18 carries a cam 30 which is adapted to engage the tail portion 31 of latch 23, so as to tilt the latch to the position shown in Fig. 5 whereby the members 16 and 26 are decoupled. Under these conditions, and assuming that clutch member 10 is stopped, the scanning drum 22 is disconnected from the drive shaft 2 and is free to coast for a fraction of a revolution permitting the drum to decelerate. In the meanwhile of course, shaft 2 and member 26 are in continuous rotation. However, when the tail 31 of latch 23 leaves cam 30, the members 16 and 26 are so displaced as to prevent the latch from re-engaging the same notch, thus causing the drum to slip back until the latch drops into the next succeeding notch. This therefore prevents the drum 22 from coasting down below a certain speed, and the number of notches provided controls the total displacement or deceleration permitted per revolution. In other words, in the absence of the auxiliary clutch, the drum 22 might, because of friction, experience a drop in coasting speed to such an amount so that when arm 11 is subsequently released, the difference in normal continuous running speed of shaft 2 and the lowered coasting speed of drum 22, would subject the shaft 2 to a comparatively sud-

den load, with resultant slipping between the clutch members 8, 9 and 10. This slippage may result in an improper phasing between drum 22 and the corresponding scanning drum with which it is to be synchronized at the opposite end of the system.

The operation of the mechanism is as follows. When the latch 23 rests in one of the notches between adjacent teeth 26 as shown in Fig. 4, the 10 collar 26 tends to drive the lead screw 17 by means of plate 16, and at the same speed as shaft 2. When cam 30 engages latch tail 31, latch 23 is tilted out of engagement with collar 26 and the speed of drum 22 will be lowered slightly 15 because of friction in its bearings and the like. Thus, there will be a relative phase displacement between members 16 and 26 until latch tail 31 disengages cam 30. Preferably, the length of cam 30 is related to the length of each tooth 25 so that when the latch tail 31 leaves cam 30 the latch 23 rides on a tooth 25 ready to engage the next succeeding notch in collar 26, whereupon the drum 22 will be positively driven for the remainder of its revolution through friction member 27 and shaft 2.

In the particular arrangement illustrated, the member 26 has eight equally spaced notches so that the drum 22 can never freely coast for more than one-eighth of a revolution. Therefore, the 20 speed of drum 22 will always be within 80 or 90% of the normal running speed of shaft 2. If desired, the positive driving of the drum by shaft 2 and member 27 may be such as to overdrive the drum thus likewise enabling the latch 13 to catch up with stop arm 11.

As the latch 23 steps from notch-to-notch, the main driving latch 13 will come into contact with the arm 11, and as soon as this position is reached the plate 16 will be driven continuously by means 40 of arm 11 and latch 13. By reason of the fact that the stop arm 11 picks up the load of the drum when the drum is coasting within 80 or 90% of the normal running speed, the shock on clutch 7 will be very slight and there will be little or 45 no slippage. In fact, with the particular arrangement disclosed, the slippage can be reduced to a substantially negligible amount, and if desired a greater number of notches may be provided in the member 26 to reduce even further 50 the possibility of slippage.

While one particular embodiment has been illustrated and disclosed herein, it will be understood that various changes and modifications may be made without departing from the spirit and scope of the invention.

What is claimed is:

1. A phasing arrangement for telegraph apparatus such as a facsimile scanning drum, comprising a driving shaft, a slip-friction clutch 60 between said driving shaft and drum, means to declutch the drum from the driving shaft to allow the drum to coast freely, and means to impart positive driving torque to the drum at intervals while coasting to maintain its coasting speed above a predetermined amount until said declutching means is again operated to cause clutching of the drum to said shaft.

2. A phasing arrangement for telegraph apparatus such as a facsimile scanning drum, comprising a continuously running driving member 70 for said drum, a driving connection between said member and said drum, said connection including a device which can be stopped while allowing the drum to coast freely with relation to said driving member, said device when released al-

lowing the driving member to impart positive driving torque to the drum, and other means to maintain said coasting speed above a predetermined amount while said device is stopped.

3. A phasing arrangement for a telegraph device such as a facsimile scanning drum, comprising a continuously running driving member, a scanning drum having substantial rotational inertia, a controllable clutch for applying power from said driving member to said drum, a one-way positive latch coupling between said driving member and said drum and which also allows said drum to coast freely with relation to said driving member when the said drum is declutched from said driving member, and means independent of said latch coupling to impart positive driving torque at intervals to said drum while coasting to maintain said coasting speed above a predetermined amount.

4. A driving arrangement for a telegraph apparatus such as a facsimile scanning drum, comprising a driving shaft, a scanning drum, a main friction clutch for coupling the driving shaft to the drum, means to decouple the drum from said main clutch, an auxiliary clutch having a member positively driven by said shaft, and means for coupling the drum to said member at intervals while the drum is coasting and while said decoupling means is decoupling the drum from said main clutch to maintain the coasting speed above a predetermined amount.

5. A driving arrangement according to claim 4 in which said member comprises a toothed ring, and the last-mentioned means includes a shiftable member rotatable with the drum and movable into and out of engagement with said toothed ring.

6. A driving arrangement for a telegraph device such as a facsimile scanner, comprising a continuously running driving shaft, a driven shaft for said drum, a scanning drum connected to said driven shaft, a slip-friction clutch between said two shafts and having a member frictionally driven from said driving shaft, a one-way latch device between said member and said driven shaft for imparting a positive torque to said driven member while allowing said drum to coast when said member is stopped, and another clutch device for coupling said driven shaft

to the driving shaft at regular intervals during each coasting rotation of the drum.

7. A driving arrangement for telegraph apparatus such as a facsimile scanning drum, comprising a continuously running driving shaft, a driven shaft for said drum, a slip-friction clutch having a member frictionally coupled to the driving shaft, a stop arm carried by said member for stopping said member without stopping the driving shaft, a driving plate fastened to the driven shaft, a pivoted latch member extending from said plate into the path of said stop arm, a toothed ring frictionally coupled to said driving shaft, and another pivoted latch member carried by said plate and selectively movable into engagement with said teeth to impart a positive torque at spaced intervals to said drum when said arm is stopped.

8. A driving arrangement according to claim 7 in which stationary cam means is provided for engaging said other latch at a predetermined point of the drum's rotation.

9. A phasing arrangement for a telegraph device such as a facsimile scanning drum, comprising a continuously running driving source for said drum, means to drive the drum from said source preliminarily to the receipt of a phasing signal, means to disconnect the drum from said driving source to allow it to coast freely, means responsive to the receipt of a phasing signal to control the connection of said driving source to said drum while the latter is coasting, and means to maintain said coasting speed above a predetermined amount pending the receipt of said phasing signal.
